UNITED STATES PATENT OFFICE

HENRY J. HARTLEY, OF HASTINGS-ON-HUDSON, NEW YORK, AND DUDLEY BAIRD, OF BERKELEY, CALIFORNIA, ASSIGNEES, BY MESNE ASSIGNMENTS, TO NICHOLS ENGINEERING AND RESEARCH CORPORATION, OF NEW YORK, N. Y., A CORPORATION OF DELAWARE

RABBLING MEANS

Application filed April 19, 1932. Serial No. 606,102.

This invention relates to furnaces and particularly to improved rabbling means especially adaptable for use in roasting furnaces of the class shown for example in U. S. Letters Patent No. 976,175 to John B. F. Herreshoff, dated November 22, 1910.

The objects of this invention include the provision of improved rabbling means involving the use of rotatable disc harrow teeth, such teeth being preferably individually mounted. According to one aspect of the invention, these teeth are so mounted that each of the same may rotate independently of the others and also rise and fall independently when passing along their path of movement. Other objects of the invention include the provision of constructions of the above indicated class, which may be adjusted and operated with a wide degree of flexibility, to efficiently and dependably meet different conditions of operation and maintenance.

Various further and more specific objects, features and advantages will appear from the detailed description given below taken in connection with the accompanying drawings which form a part of this specification.

The invention consists in the novel features, arrangements and combinations of parts embodied by way of example only in the apparatus hereinafter described.

In the drawings—

Fig. 1 represents in central vertical section the top part of a multiple hearth roasting furnace embodying the invention;

Fig. 2 is a top plan view showing the construction of a rabble arm as mounted in a furnace according to the invention;

Fig. 3 is a sectional view of the rabble arm of Fig. 2, this section being taken substantially along the line 3—3 of Fig. 2;

Fig. 4 is a view similar to Fig. 2, but showing an alternative embodiment of the invention as applied to a furnace hearth having peripheral discharge openings; and

Fig. 5 is a view similar to Fig. 4 but showing a rabble arm construction as applied to a furnace hearth having a central discharge opening.

Although the invention is applicable to furnaces of various types, in the particular ex-

ample illustrated in Fig. 1 the furnace as shown may comprise a plurality of vertically spaced or superposed circular hearths, one of which is indicated at 10. These hearths are surrounded and supported in the usual manner by a cylindrical furnace wall 11. The usual rotatable and internally cooled shaft 12 extends vertically up through the furnace substantially along the central axis thereof. This shaft is provided with a series of rabble arms as at 13 and 14 extending radially from the shaft into the space between succeeding hearths. A hopper is indicated at 15 for discharging the material to be treated into the furnace through an ore-luted feeding device 16. The material entering the furnace through the feeding device, falls upon a delivery bed 17 where it may be given a preliminary heating and is effectively dried. Rabble arms as at 18 and 19 extend from the central shaft radially over the delivery bed 17, and these rabble arms, as well as various of the other rabble arms in the furnace if desired, may be provided with rabbling means according to this invention.

From the delivery bed 17 the ore may be fed through an opening as at 20 also provided with an ore-luted feeding device as at 21, from which the ore may fall to the hearth 10.

We will now describe in further detail the rabble tooth arrangement such as is shown in connection with the rabble arms 18 and 19, Figs. 2 and 3 showing this arrangement more fully.

The rabble arms 18 and 19 may be cast of suitable heat resisting material or if desired, the same may be formed of standard steel tubing, but in either event, means may be provided at the lower side of the arm for slidably receiving rabble tooth supporting means. For example, as shown in Fig. 3, the lower surface of the rabble arm may be cast of a shape to provide a groove at 22 for slidably receiving tongue portions 23 of corresponding shape, formed on rabble supporting members as at 24. The rabble arms may be provided in the usual way with an internal cavity as at 25 and an internal cooling fluid conduit as at 26.

In the example of the invention illustrated

in Figs. 2 and 3, the rabble tooth supporting members 23 may each be provided with a lug as at 27, to which a supporting arm 28 may be connected. Supporting arm 28 in turn may be pivotally connected as at 29 to a link 30 which carries a shaft or stud 31 on which a disc tooth 32 is rotatably mounted. The lug 27 may be adjustably connected to the arm 28 as by a bolt or pin as indicated, and if desired, the engaging surfaces of the members 27 and 28 around this bolt or pin may be provided with teeth extending radially from the bolt. With this arrangement when the bolt is loosened, the arm 28 may be adjusted at various different or desired angular positions in reference to the rabble arm and then the bolt may be tightened for securely locking the arm 28 in the desired adjusted position. The connection at 29 between the arm 28 and link 30 preferably forms a loose flexible or pivoted joint which permits the rabble discs to individually rise and fall along their path of travel in order that the discs may pass over abnormally large pieces or accumulations of the material being treated without danger of breakage of the parts or jamming of the operation thereof.

The above described arrangement provides a ready means for adapting the conventional forms of rabble arms to the features of this invention. However, in Figs. 4 and 5 additional embodiments are shown wherein the rabble arms are more especially constructed for the purposes of this invention. As shown in Fig. 4 the rabble arm itself may comprise a tubular member as at 33 of uniform cross-section, the outer end of this member being provided with a plug as at 34, and a cooling fluid conduit as at 35 being provided within the arm. According to this embodiment of the invention, it will be noted that each of the rabble discs as at 36 is rotatably mounted upon a stud as at 37, which in turn is supported on a link 38 corresponding in part to the functions of the link 30 in the embodiment above described. The link 38 may be pivotally connected as at 39 to hollow supporting members as at 40 which embrace the arm 33. If desired, the members 40 may be so constructed as to freely turn about the arm 33 to permit the rabble discs to ride up and down when following the path of travel over the hearth. Ordinarily the connection 39 between the members 38 and 40 may be adjustable, although arranged to be clamped and locked the same as the connection at 27 in the embodiment illustrated in Fig. 3 whereby the rabble discs may be individually adjusted to drag at the desired angle in respect to the rabble arm. However, under some circumstances in treating certain materials, it may be found desirable to allow free pivotal movement at the connection 38 thereby giving the rabble discs freedom for universal movement within limits.

With the arrangement shown in Fig. 4 the rabble supporting members 40 may be suitably spaced to provide the desired spacing between rabble discs, by the use of cylindrical spacer members as at 41. The rabble supporting member 42 at the outer end of the rabble arm if desired, may be provided with a scraper or rabble tooth of conventional form as at 43 for scraping the material under treatment into the discharge openings as at 44 provided at the periphery of the hearth.

The supporting members 40 and spacer members may be readily slid on or off at the outer end of the rabble arm 33 and in order to removably retain such members on the arm, a transverse pin as at 46 may be provided to extend through suitable apertures in the end of the arm and through the end plug 34. As indicated in Figs. 4 and 5, portions of the lower surfaces of the hangers 40 and spacer members 41 may be cut away at 45. Such cut-away portions enable one to apply a suitable tool or hook to these members to facilitate removal of the same. Also, the cutting away of such portions of course results in some saving of weight and material.

In the event that it is desired to prevent vertical movement of the rabble discs of the type shown in Figs. 4 and 5, the hangers 40 and the rabble arms may be formed to provide a tongue and groove connection such as shown at 22 and 23, Fig. 3.

The embodiment of the invention illustrated in Fig. 5 is similar to that of Fig. 4 with the exception that it will be noted that the disc rabbles are mounted to deflect the material under treatment inwardly instead of outwardly of the hearth, thereby permitting the provision of an internal discharge opening as at 47 in lieu of the peripheral openings 44 as above referred to.

It will be understood that under some circumstances either one or both of the joints as at 27 and 29 in Fig. 3 and as at 39 in Fig. 4 may be omitted with the parts permanently and rigidly attached or made integral at these points.

The usual practice as followed in the design of furnaces of this general type may be followed as to constructional details which are not specifically referred to herein and in this connection reference is also hereby made to the above mentioned Herreshoff patent and to the patent to Baird, No. 1,671,395, granted May 29, 1928.

With the above described arrangements it will be observed that each of the disc rabbles may be independently adjusted at the proper angle, which may be determined by trial, so that the ore or other material being dried or treated on the hearth will be progressed over each area of the hearth at the proper rate. This feature involves various advantages. For example, the area available near the peripheries of the hearths for treating

the ore is much greater than the hearth area available near the central portions of the hearths. Therefore if the ore is to be efficiently treated and at the same time progressed over the hearths so that no prohibitive accumulations will occur at any point, then it will usually be advisable to move the ore more rapidly over the central areas and to this end the disc rabbles nearer the center 5 may be adjusted at progressively greater angles in respect to their paths of travel, as is indicated in Figs. 4 and 5. The disc rabbles nearer the periphery of the hearths may be adjusted at lesser angles or at angles 10 such that the movement of the ore will be slow enough to readily permit the desired degree of drying or other treatment.

It will be noted further that with the above described arrangements the individual 20 mounting of the disc rabbles is such that spacer members of various sizes may be used to space the discs at the proper distances, depending upon the character of the material treated, and also any of the discs which 25 may become excessively worn or otherwise defective, may be individually and quickly replaced or repaired without the necessity of removing the other discs on the same rabble arm unless it is so desired. Also, since each 30 of the discs is separately rotatable, if one of the discs should become temporarily jammed or its operation should be otherwise imperfect, the remaining discs may still be free for proper operation and if excessive accumulations or large lumps of the ore occur 35 at any point, any of the discs will be free to individually rise and fall to accommodate such conditions.

Although as indicated in Fig. 1, the invention 40 is shown as applied to the top drying hearth or the delivery bed of the furnace, it will be understood that if desired this arrangement may be applied in a similar manner to other hearths within the multiple 45 hearth furnace, as for example is indicated by Figs. 4 and 5 which illustrate the other embodiments as applied to internal hearths.

While the invention has been described with respect to certain particular preferred 50 examples which give satisfactory results, it will be understood by those skilled in the art, after understanding the invention, that various changes and modifications may be made without departing from the spirit and scope 55 of the invention, and it is intended, therefore, in the appended claims to cover all such changes and modifications.

What is claimed as new and desired to be secured by Letters Patent of the United 60 States is:

1. In combination a furnace having a vertically extending rotatable shaft, rabble arms extending substantially radially from said shaft, and a plurality of rotatable disc 65 rabbles connected to said arms by means per-

mitting each of said disc rabbles to rise and fall independently when moving along its path of travel.

2. In combination a furnace having a vertically extending rotatable shaft, rabble 70 arms extending substantially radially from said shaft, a plurality of disc rabbles, and means individual to each of said rabbles for mounting the same and for connecting the same to one of said rabble arms. 75

3. In combination a movable rabble arm, a rotatable disc rabble, and means for connecting said rabble to said arm comprising a hollow cylindrical member embracing and rotatable about said arm. 80

4. In combination a movable rabble arm, a plurality of disc rabbles, means individual to each of said rabbles and adapted to be slidably received on said arm for connecting the rabbles to the arm, and spacer members 85 also slidably received on said arm for spacing apart said connecting means.

5. In combination a movable rabble arm, a plurality of rotatable disc rabbles, and means for connecting said rabbles to said 90 arm whereby the rabbles are dragged along arcuate paths of movement by said arm, said connecting means being adjustable individually as to each of said rabbles whereby the several rabbles may be carried at various 95 different angular relationships with respect to their paths of travel.

6. In combination a movable rabble arm, a plurality of disc rabbles, and means for connecting said rabbles to said arm whereby 100 each of said rabbles is rotatable independently of the others.

In testimony whereof we have signed our names to this specification.
